UNITED STATES PATENT OFFICE.

RALPH E. BURTON, OF WASHINGTON, DISTRICT OF COLUMBIA, ASSIGNOR TO JOHN W. WEEKS, SECRETARY OF WAR OF THE UNITED STATES OF AMERICA, TRUSTEE.

GOVERNOR.

Application filed May 6, 1922. Serial No. 559,100.

(GRANTED UNDER THE ACT OF MARCH 3, 1883; 22 STAT. L. 625.)

The invention described herein may be used by the Government, or any of its officers or employees in prosecution of work for the Government, or by any other person 5 in the United States, without payment of any royalty thereon.

This invention relates to governors, and more particularly to a form especially adopted for use in combination with a well known 10 form of magneto, whereby the spark, for instance, in the combustion chamber of an internal combustion engine, may be discontinued when the speed of rotation has reached a predetermined rate.

15 The objects are to provide a simple, durable and inexpensive device that may be applied to a magneto by simply adding the few parts required, and only slightly changing one of the parts of the magneto as originally placed on the market.

20 A further object is to provide a device of a character that may be sold as an attachment for a magneto and may be applied by one that is not necessarily an expert 25 mechanic.

25 A further object being to break the high tension current just prior to its discharge from the distributor at the end of the magneto by opening a gap between the end of 30 the high tension pencil and the contact plate in the rotor of the distributor, when the motor to which the magneto is attached, has passed a predetermined R. P. M.; said structure also providing for the automatic re-establishment of the current through the 35 parts when the engine has resumed its predetermined maximum R. P. M.

For purposes of illustration, one form of 40 this device is shown, it being understood that minor detail changes in construction may be resorted to without departing from the spirit of the invention.

Similar numerals indicate corresponding 45 parts in all the figures of the drawings in which:

Fig. 1 is a vertical section of my improved governor, showing adjoining fragmentary parts of a well known magneto, as at present placed on the market.

50 Fig. 2 is a detailed perspective view of the governor body, or spider.

Fig. 3 is a similar view of the governor slide sleeve.

Fig. 4 is a similar view of the distributor 55 rotor.

Fig. 5 is a similar view of the governor arms, links, fly balls and springs, assembled.

Fig. 6 is a similar view of the magneto pencil.

Reference now being had to the drawings 60 by numerals, 1 indicates a well known form of magneto, 2 the high tension brush holder, 3 indicates one member of the safety spark gap, connected by flexible arm 4, with the brush holder 2.

The usual distributor rotor magneto gear 5, and its driving pinion 6, are shown in Fig. 1. Ordinarily the distributor block 7, with its insulating ring 8, is mounted directly on the magneto 1, and the distributor rotor 9 70 is mounted directly on the gear 5.

When this improved governor is applied, the above named parts are in no way altered as to their structure, but are simply detached from the parts mentioned and a governor 75 housing, or tubular extension 10, is inserted between the magneto casing 1 and its distributor block 7, and a governor body or spider 11, is inserted between the gear 5 and the distributor rotor 9. All mounting and 80 securing means corresponding, and are interchangeable.

To mount what is known as the high tension pencil in the form of magneto shown, it has always been necessary to insert the outer 85 point of the pencil into the distributor rotor and telescope a sleeve against the tension of a spring at the other end of the pencil in order to adjust the bifurcated inner end of the pencil on the high tension brush holder 2. 90

Said pencil 12 is in no way altered as to structure, but is simply lengthened to reach its seat in the rotor 9 in its adjusted or outer position. By reference to Fig. 1, it will be seen that the pencil is provided with the reduced inner end 13, adopted to form an abutment for one end of a coil spring 14, located in a telescoping sleeve 15, said sleeve being provided with the usual bifurcated end 16, adopted in its usual way to straddle the 100 shank or terminal of the high tension brush holder.

The pencil may be of insulating material and conductor 17 may extend through same and come into contact with the distributor 105 contact plate 18, which, in turn, transfers

the electrical energy to the distributor contact brushes 19, and from these out through cables (not shown) secured by the terminal nuts all in the usual manner.

5 By reference to Figs. 1 and 2, the governor body or spider 11, consists of end plates 20 and 21, connected by parallel members 22. The plates 20 and 21 are provided with central openings 23 through which the pencil extends. Plate 20 is provided with ears 24, between which governor arms 11, are pivotally mounted on pins 25, said plate 20 being permanently secured by screws 26 to the gear 5 of the magneto.

10 To the outer plate 21, is secured by screws 27, the magneto rotor 9.

A governor slide sleeve 28 is mounted for longitudinal movement on the axis of rotation in a central chamber 29, in the rotor. 20 Said sleeve 28 being provided with ears 30, between which one end of the governor arm links 31 are mounted on pins 32. The opposite ends of links 31 are mounted on pins 33, in ears 34, mounted on or forming an 25 integral part of the governor arms.

Any preferred form of tension springs 35 may be mounted on the governor arms such as shown, and may be secured at their ends in apertured projecting ends of bearing pins 33, and tend to retract the governor arms.

30 Fly balls 36 are shown adjustably mounted on screw threaded extensions 37, of the governor arms, and may be secured in their adjusted positions on said arms by lock nuts 38.

35 By adjusting the fly balls 36 away from the axis of rotation of the governor, the maximum or operating R. P. M. will be reduced.

40 The high tension pencil 12 is provided with shoulder 39, immediately adjacent to the inner end of the sleeve 28, against which the sleeve comes into contact when the governor operates.

45 In the use of this device, a positive check is obtained against racing the engine, the fly balls are adjusted and locked in the position to operate at a maximum predetermined R. P. M. When said speed is reached, 50 the fly balls are thrown out against the tension of springs 35, arms 40 swing out, carrying with them the inner ends of links 31, the outer ends being secured to sleeve 28 will cause same to be partially withdrawn from

55 the chamber 29 in the rotor, causing said sleeve to come into contact with shoulder 39 of the pencil and move same back against the tension of compression spring 14, withdrawing the outer end 41 of pencil 12 out of 60 engagement with the distributor plate 18, thereby interrupting the transfer of current through the several terminals, and the ignition spark will be discontinued in the several cylinders until the speed of the governor is

65 again reduced to its maximum operating speed, at which time spring 35 will retract governor arms 40, which will in turn slide sleeve 28 back to its normal position and permit the high tension pencil under the pressure of spring 14 to return to its normal position and reestablish the electrical connection between the magneto and the distributor plate.

Having thus described my invention, what I claim as new and desire to secure by Letters Patent is:

1. The combination with a magneto having a longitudinally moveable high tension pencil, a distributor in electrical contact with the pencil, and a governor mechanism provided with means for moving said pencil and breaking the electrical connection between said pencil and the distributor.

2. The combination with a magneto having a distributor block, a distributor rotor having a contact plate, a gear for rotating the distributor and a longitudinally moveable high tension pencil normally in contact with the distributor contact plate, of a governor mechanism having a rotary body portion arranged between the gear and the rotor and adapted to move the pencil out of engagement with said contact plate.

3. The combination with a magneto having a distributor block, a distributor rotor having a contact plate, a gear for rotating the distributor rotor and a longitudinally moveable high tension pencil normally in contact with the distributor contact plate, of a governor mechanism having a body portion mounted on the gear and the rotor, governor arms supported on the body portion, operating to move the pencil out of engagement with the contact plate.

4. The combination with a magneto having a distributor block, a distributor rotor having a contact plate and gear for rotating a distributor, and a longitudinally moveable high tension pencil normally in contact with the distributor contact plate, of a governor mechanism having a body portion, a sliding sleeve, governor arms connecting the body portion and sleeve, adapted to operate the sleeve to move the pencil out of engagement with the plate.

5. The combination with a magneto having a rotor provided with a contact plate and gear for rotating same and a high tension pencil having a shoulder, of a governor mechanism comprising a body portion and sleeve slidably mounted on the rotor adapted to come into contact with said shoulder, and governor arms mounted on the body portion and connected with the sleeve, substantially as described.

6. The combination with a magneto having a rotor provided with a contact plate and gear for rotating same, of a high tension pencil having a shoulder, a governor mechanism comprising a body portion se-

cured to the gear and rotor, and governor arms mounted thereon, a sleeve slidable in the rotor and adapted to come into contact with said shoulder, and links connecting the 5 governor arms and sleeve substantially as and for the purpose specified.

7. The combination with a magneto having a gear, a rotor provided with a contact plate, of a spring pressed high tension pencil normally in contact with the plate adapted for slight longitudinal movement and provided with a shoulder, a governor mechanism comprising a body member having end plates connected by parallel 10 arms, mounted on said gear and supporting said rotor, governor arms mounted on one of said plates and carrying adjustable fly balls, a sleeve slidably mounted in an aperture in the rotor adapted to be brought into 15 contact with said shoulder to move the pencil out of contact with the plate, links pivotally mounted at one end on the sleeve and at the other end to the governor arms and adapted to move the sleeve substantially 20 as described.

8. A governor mechanism for magnetos, consisting of a body portion adapted to be

interposed between the magneto gear and the magneto rotor for rotation therewith, a high tension pencil, a distributor plate 30 and a sleeve mounted in the rotor and pierced by the high tension pencil, weighted governor toggle arms secured to said body member and said sleeve and adapted when rotated beyond a predetermined speed 35 to move the high tension pencil away from its contact with the distributor plate and a housing inclosing the space between the magneto and its distributor block, substantially 40 as described.

9. A governor mechanism for magnetos, consisting of a body portion adapted to be interposed between the magneto gear and the magneto rotor for rotation therewith, a high tension pencil, a distributor plate 45 and a sleeve mounted in the rotor and pierced by the high tension pencil, weighted governor toggle arms secured to said body member and said sleeve, and a housing inclosing the space between the magneto and 50 its distributor block, substantially as described.

RALPH B. BURTON.
